(57) **CLAIM**

The ornamental design for a weighing scale with foot sensors,
as shown and described.

DESCRIPTION

FIG. 1 is a perspective view of the scale.

FIG. 2 is a top view of the scale.

FIG. 3 is side view of the scale.

FIG. 4 is a front view of the scale; and,

FIG. 5 is a back view of the scale.

The broken line showing of structural features and indicia is
included for the purpose of illustrating non-claimed subject
matter and forms no part of the claimed design.
